EASEL BACK

Gordon E. Nichols, Middleboro, Mass., assignor to
 Winthrop-Atkins Co., Inc., Middleboro, Mass., a
 corporation of Massachusetts

Application March 9, 1946, Serial No. 653,338

15 Claims. (Cl. 248—35)

1

This invention pertains to foldable easels such as are used as mounts for photographs, calendars, etc., and relates more especially to an improved back for such an easel.

Customarily, an easel of this type comprises a back of stiff sheet material such as cardboard, to whose forward face the frame elements or other parts designed to hold and protect the photograph or calendar are secured. A leg is hinged to the back to hold the latter in the desired upright position of use, and there is usually a brace designed to connect the back and leg at a substantial distance from the hinge axis of the leg, so as to hold the leg and back in the desired downwardly divergent position of use. The brace should hold the leg firmly when in use, but should be easily releasable to permit the easel, including the leg and brace, to be folded flat when desired. In some of the prior devices of this kind the proper disposition of the leg and brace requires a considerable degree of manipulative skill, and users are sometimes annoyed by the difficulty (even though it may in fact be very slight) encountered in setting up the easel. Moreover, in some of the prior devices it is hard to tell whether or not the brace has actually been positioned properly, and in consequence the easel sometimes falls down, even though the user believes that he has properly adjusted the brace and leg.

The present invention has for one of its objects the provision of an improved easel back provided with a leg and brace, and so designed that the mere operation of swinging the leg to the divergent position of use automatically sets the brace in the operative position. A further object is to provide an easel back provided with a leg and brace, and so devised that when the leg and brace are moved to the position of use, a distinct snap is felt and/or heard when the parts finally assume the proper relative position. A further object is to provide a device of this type wherein the brace may readily be disengaged from the leg preparatory to folding the easel. A further object is to provide a device of this kind in which the leg, brace and back may be integral parts of a single piece of sheet material. Other and further objects and advantages of the invention will be pointed out in the following more detailed description and by reference to the accompanying drawings, wherein.

Fig. 1 is a plan view of a blank employed in making the easel back of the present invention;

Fig. 2 is a front elevation, showing the blank folded to form the back;

2

Fig. 3 is a rear elevation of the folded back; Fig. 4 is a perspective view, looking toward the rear side of the easel back and showing the parts in the positions which they occupy while the easel is being set up; and

Fig. 5 is a view similar to Fig. 4 but showing the parts in their final operative position of use. Referring to the drawings, the blank illustrated in Fig. 1 consists of a unitary piece of sheet material, for example cardboard, of the requisite stiffness to furnish the proper support, this material having a substantial degree of natural resiliency so that if bent it tends to return to its original flat condition. This blank comprises the part 1 hereinafter referred to as the front or panel portion of the easel back, and the part 2 hereinafter referred to as the leg. The parts 1 and 2 are integrally joined along the horizontal line 3 where the material is indented, scored or 10 perforated to provide a hinge joint about which the parts 1 and 2 may be folded into substantially parallel face-to-face relation. While in the preferred construction the parts 1 and 2 are integrally joined, it is within the scope of the invention to make the panel and leg of separate pieces of material and to unite them along the line 3 to form a hinge joint in any suitable and convenient manner. The edges 4 and 5 of the parts 1 and 2 respectively are those edges upon 20 which the easel back stands when in use.

The panel member 1 is provided with a large central aperture 6 into which projects the brace member 7. This brace member is integral with the panel 1 and united to the latter along the line 8, here shown as slightly curved, and which may be defined by a light scoring or indentation, if desired. However, the brace 7 should not swing freely about the line 8 as a hinge, since it is desirable, in accordance with the present invention, that the brace 7 possess a substantial resilient tendency to remain in the plane of the panel 1, and to return to said plane when bent about the line 8. This tendency is accentuated by the use of the curved hinge line. As illustrated, the brace 7 is free from the panel 1 along the lines 9 and 10. The brace 7 is provided with a centrally disposed, more or less T-shaped slot comprising the vertically elongate guide portion 11 having the parallel edges E, the slot having the transverse or cross-bar portion 12 substantially wider than the guide portion 11. The edges E of the guide portion 11 intersect inclined edges 13 of the transverse part 12 of the slot, this transverse portion or recess 12 having the curved edge 55 14 which intersects the edges 13 at the points 15,

the recess thus being of somewhat lenticular shape and widest between the points 15.

The leg 2 is provided with a central aperture 16 having the upper edge 17 from which a tongue projects downwardly into the recess 16. This tongue is integral with the leg 2 and comprises a base portion 18 of a width approximating the width of the aforesaid recess 12 between the points 15. The tongue also comprises a central tab 19, here shown as of substantially semi-circular contour, and of a width substantially equaling the width of the guide portion 11 of the slot in the brace 7. The lower edge of the base portion 18 of the tongue is shaped to provide substantially horizontal abrupt shoulders at 20.

Having provided the blank as above described, and as shown in Fig. 1, this blank is folded along the hinge line 3 and the brace 7 is projected through the aperture 16 so that the parts assume the positions shown in Figs. 2 and 3, with the panel 1 and leg 2 in substantial contact and the free or upper end portion of the brace 7 in substantial contact with the rear surface of the leg 2. In projecting the brace 7 through the aperture 16, it is necessary to bend the brace about the line 3 and when the brace is released its tendency to return to the plane of the panel 1 is such that it exerts a resilient force against the rear face of the leg 2, such as to tend to hold the leg in contact with the panel 1, thus holding the back in folded condition.

It is to be understood that the panel portion 1 forms the front element of the easel back and that to the forward surface of this panel 1 there may be secured such other parts as may be desired in the construction of the completed easel. However, since these parts are not concerned in the present invention, no attempt has been made to illustrate them here.

Assuming that the easel has been completed by mounting on the front face of the panel 1 the requisite elements, and that it is desired to set up the easel for use (it now being in the condition shown in Fig. 3), the user merely grasps the lower part of the leg 2 and swings it rearwardly about the hinge line 3, relatively to the panel 1 (Fig. 4). As soon as force is applied to swing the leg 2 rearwardly into divergent relation to the panel 1, the shoulders 20 of the tongue portion of the leg start to bear against the marginal portions of the brace 7 adjoining the edges E of the slot 11. These shoulders exert a camming action as the leg is gradually swung rearwardly, thus pressing the brace downwardly toward horizontal position. This intermediate position of the parts is illustrated in Fig. 4. This movement continues until the shoulders 20 of the tongue reach the junction of the edges E of the slot 11 with the inclined edges 13 of the recess 12. As soon as the shoulders 20 reach these edges 13, a mutual camming action takes place, which causes the shoulders to move quickly into the widest part of the recess 12, thus releasing the brace and permitting it, in response to its natural resilience, to snap quickly upward until its upper surface contacts the edge 17 of the aperture 16.

The vertical depth of the base portion 18 of the tongue, is preferably of the order of $\frac{1}{4}$ inch or thereabouts, and thus as the brace is released from the shoulders 20, it suddenly moves through this distance with the result that it strikes the edge 17 a sharp blow, causing a distinct snapping sound which thus apprises the user of the fact that the parts have reached their final operative

or interlocked position. When in this operative position, the base of the tongue is disposed at the widest part of the recess 12, and by reason of the shape of this recess the leg cannot move in either direction lengthwise of the brace, so long as the tongue remains in this part of the slot. When in this position (Fig. 5) the free or rear end portion of the brace is exposed at the rear part of the leg, and by merely pressing down upon this exposed portion of the brace the brace may be disengaged from the base part of the tongue, thus permitting the leg to be swung back to its folded position.

The back member thus provided is of very simple construction, but very easy to operate both as respects setting it up for use and in returning it to folded position. Moreover, as already noted, when, in setting it up, it reaches the operative position, the snapping of the parts, as they interlock, gives notice that the parts have been set up properly and when thus set up the interlocking of the tongue with the recess 12 holds the parts rigidly in position so that the leg can move in neither direction until the tongue is purposely disengaged from the recess.

While one desirable embodiment of the invention has been illustrated by way of example, it is to be understood that the invention is broadly inclusive of such modifications as fall within the scope of the appended claims.

I claim:

1. A foldable easel back comprising a stiff panel having a leg and a brace connected thereto, the leg and brace having complementary interlocking parts operative when engaged to hold the leg in downwardly divergent position of use relatively to the panel, the lower end of the brace being so united to the panel that the brace tends to lie in the plane of the panel, the connection between the leg and panel comprising hinged means permitting the leg to swing outwardly from the panel, said leg having an aperture through which the brace projects, the tendency of the brace to lie in the plane of the panel being effective normally to keep the leg folded.

2. A foldable easel back comprising a stiff panel having a leg and a brace connected thereto, the leg and brace having complementary interlocking parts operative when engaged to hold the leg in downwardly divergent position of use relatively to the panel, the lower end of the brace being so united to the panel that the brace tends to lie in the plane of the panel, the leg being hinged at its upper end to the panel and having an aperture through which the brace projects, the leg having a downwardly directed locking tongue at the upper edge of its aperture, and the brace having an elongate guiding slot which receives said tongue while the leg is being moved to operative position.

3. A foldable easel back comprising a stiff panel having a leg and a brace connected thereto, the leg and brace having complementary interlocking parts operative when engaged to hold the leg in downwardly divergent position of use relatively to the panel, the lower end of the brace being united to the panel, the leg being hinged at its upper end to the panel and having an aperture through which the brace projects, the leg having a downwardly directed tongue at the upper edge of its aperture, the tongue comprising a base portion and a relatively narrow central tab, and having abrupt shoulders where the tab emerges from the base portion, the brace having an elongate guide slot of a width to accommodate said

tab, said slot terminating in a transversely extending recess of a width to receive the base portion of the tongue.

4. A foldable easel back comprising a stiff panel having a leg and a brace connected thereto, the leg and brace having complementary interlocking parts operative when engaged to hold the leg in downwardly divergent position of use relatively to the panel, the lower end of the brace being united to the panel, the leg being hinged at its upper end to the panel and having an aperture through which the brace projects, the leg having a downwardly directed tongue at the upper edge of its aperture, the tongue comprising a base portion and a relatively narrow central tab projecting from the lower end of the base portion, the tongue having substantially horizontal shoulders where the tab protrudes from the base, the brace having a substantially T-shaped slot comprising an elongate guide portion having parallel edges and of a width just sufficient to accommodate said tab with a free sliding fit, the edge of the guide portion merging with upwardly divergent edges defining the bottom of the crossbar of the T-slot, the maximum width of said crossbar portion of the slot being sufficient to accommodate the base of the tongue.

5. A foldable easel back comprising a stiff panel having a leg and a brace connected thereto, the leg and brace having complementary interlocking parts operative when engaged to hold the leg in downwardly divergent position of use relatively to the panel, the lower end of the brace being so united to the panel that the brace tends to lie in the plane of the panel, the leg being hinged at its upper end to the panel and having an aperture through which the brace projects, the leg having a downwardly directed tongue at the upper edge of its aperture, the tongue comprising a base portion and a relatively narrow central tab, and having shoulders where the tab emerges from the base portion, the brace having an elongate guide slot to receive said tab, the slot terminating in a transverse recess of a width to receive the base portion of the tongue, the height of the base portion, between the upper edge of the aperture in the leg and said shoulders, being such that, as the shoulders disengage the margin of the guide slot the base portion of the tongue snaps with substantial force against the upper edge of the aperture in the leg.

6. A foldable easel back comprising a panel, a leg and a brace, the leg being hinged at its upper end to the panel and having an aperture intermediate its ends, the upper edge of the aperture being substantially horizontal, the brace being connected at its forward end to the panel and always projecting through the aperture in the leg, the brace having a transversely extending recess near its rear end, and the leg having a tongue which fits into said recess and thereby prevents movement of the leg lengthwise of the brace when the device is in use.

7. A foldable easel back comprising a panel, a leg and a brace, the leg being hinged at its upper end to the panel and having an aperture intermediate its ends, the upper edge of the aperture being substantially horizontal, the brace being connected at its forward end to the panel and always projecting through the aperture in the leg, the brace having a substantially lenticular transversely extending recess near its rear end and the leg having a tongue projecting from the upper edge of its aperture and of a width approximating the maximum width of said

recess and which, when seated in the recess, prevents movement of the leg lengthwise of the brace.

5. 8. A foldable easel back comprising a stiff panel of sheet material and a leg and a brace each integral with the panel, the upper end of the leg being hinged to the panel so as to swing freely, and the forward end of the brace being hinged to the panel at a substantial distance from the hinge axis of the leg, the hinge connection of the brace to the panel being such that the brace resiliently resists force applied for swinging it out of the plane of the panel, the leg having an aperture through which the brace protrudes, the brace tending to lie in the plane of the panel and having portions engaging the leg in its folded position to hold it folded.

20 9. A foldable easel back comprising a panel of stiff sheet material having an aperture in its midportion, a brace integrally joined to the panel at the lower edge of said aperture, a leg hinged at its upper end to the upper edge of the panel, the leg having a central aperture with a stiff locking tongue projecting down into the central 25 aperture from the upper edge of the latter, and the brace having an elongate slot designed to receive said tongue, the slot and tongue being so shaped that when inter-engaged the leg cannot move lengthwise of the brace in either direction.

30 10. A foldable easel back comprising a panel of stiff sheet material having an aperture in its midportion, a brace integrally joined to the panel at the lower edge of said aperture, a leg hinged 35 at its upper end to the upper edge of the panel, the leg having a central aperture through which the brace always projects, the leg and brace having complementary parts which prevent the brace from engaging the upper edge of the 40 aperture in the leg until the leg has been swung nearly to its operative position, said cooperating parts being so constructed and arranged as to permit the brace suddenly to snap against said upper edge as the leg reaches its operative position.

45 11. A foldable easel back comprising a panel of stiff sheet material having an aperture in its midportion, a brace integrally joined to the panel at the lower edge of said aperture, a leg hinged 50 at its upper end to the upper edge of the panel, the leg having a central aperture through which the brace projects, the leg and brace having engaging parts which act to cam the brace toward its operative position as the leg is swung 55 rearwardly, thereby placing the brace under bending stress, said parts being so constructed and arranged that as the leg reaches its operative position said parts disengage thereby permitting the brace to snap up against the upper edge of said central aperture.

60 12. A foldable easel back consisting of an integral piece of stiff sheet material and comprising a panel, a leg hinged to the upper edge of the panel, and a brace joined at its forward edge 65 to the panel and which tends, by reason of the resiliency of the material, to lie in the plane of the panel, the leg having an aperture through which the rear portion of the brace projects, the leg and brace having parts which engage as the leg is being swung rearwardly, thereby forcing the free end of the brace downwardly toward its operative position.

70 13. A foldable easel back consisting of an integral piece of stiff sheet material and comprising 75 a panel, a leg hinged to the upper edge of the

panel, and a brace joined at its forward edge to the panel and which tends, by reason of the resiliency of the material, to lie in the plane of the panel, the leg having an aperture through which the brace projects, the leg and brace having elements which engage and which by a cam-like action force the brace downwardly toward operative position as the leg is swung rearwardly.

14. A foldable easel back consisting of an integral piece of stiff sheet material and comprising a panel, a leg hinged to the upper edge of the panel, and a brace joined at its forward edge to the panel and which tends, by reason of the resiliency of the material, to lie in the plane of the panel, the leg and brace having inter-engaging parts operative to hold the leg in its operative position, the resiliency of the brace being such that when said parts are disengaged the easel tends to fold automatically by return of the brace to the plane of the panel.

15. A foldable easel back consisting of an integral piece of stiff sheet material and comprising a panel, a leg hinged to the upper edge of the panel, and a brace joined at its forward edge to

the panel and which tends, by reason of the resiliency of the material, to lie in the plane of the panel, the leg having an aperture through which the brace always projects, the leg and brace having inter-engaging parts cooperative to hold the leg in operative position, the resiliency of the brace being such that when said parts are disengaged the brace automatically returns the leg to folded position.
